UNITED STATES PATENT OFFICE.

RICHARD L. CLEMENTS, OF IRVINGTON, NEW JERSEY.

SOLDERLESS CAN-SEALING APPARATUS.

Application filed February 27, 1922. Serial No. 539,556.

To all whom it may concern:

Be it known that I, RICHARD L. CLEMENTS, a citizen of the United States, residing at Irvington, in the county of Essex and 5 State of New Jersey, have invented certain new and useful Improvements in Solderless Can-Sealing Apparatus, of which the following is a specification.

This invention relates to the art of sealing receptacles made of tin or like sheet material, and has particular reference to the sealing of cans without solder.

Among the objects of the invention is to produce a machine or mechanism for sealing metal cans much more rapidly and more efficiently than heretofore has been practised and at the same time to reduce to a minimum the percentage of failures to make proper seal.

20 Another object of the invention is to provide an apparatus of the character set forth including a can seal contact member or pad which is relatively stationary and whereby the seal is held reliably in proper position 25 for and during the sealing action.

A further object of the invention is to provide means for adapting the mechanism to and for operation by various types of standard motors and with means carried by the 30 motor casing for holding the aforesaid seal pad or contact member stationary.

A still further object of the invention is to provide in a more precise manner than heretofore for the adjustment of such parts 35 of the mechanism as require delicate adjustment for the effective sealing action thereof.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is 45 had to the accompanying drawings, in which like reference characters designate the same parts in the several views, and in which—

Figure 1 is a vertical section of a preferred embodiment of the invention shown as applied to one well known type of motor from 50 which the rotating parts of the mechanism may be driven.

Fig. 2 is a vertical sectional view of the lower part of my improvement taken at 55 right angles to Fig. 1, and showing espe-

cially the arrangement and action of the starting rollers.

Fig. 3 is a horizontal section on the line 3—3 of Fig. 2 showing the roller actuating means in plan.

Fig. 4 is a horizontal sectional detail on the line 4 of Fig. 1.

Fig. 5 is a vertical sectional view of a modified motor connection.

Figs. 6, 7, and 8 are diagrams indicating 65 progressive steps in the sealing action.

Fig. 9 is a horizontal detail on the line 9—9 of Fig. 1.

Figs. 10 and 11 are details described 70 below.

Referring now more specifically to the drawings, I show a motor M having a casing 10 and a bearing hub 11, the latter being arranged at the bottom of the casing and at one side of the axis of the motor shaft 12 to 75 which is fixed a pinion 13. Within the hub 11 is arranged a thrust bearing ring 14 with relation to which is a companion ring 15 fixed in any suitable manner to a sleeve or hollow shaft 16 projecting upward into the 80 motor casing and to whose upper end is fixed a gear 17 meshing with said pinion 13. Within the motor casing is fixed in any suitable manner a bracket 18 to which is secured, by means preferably of a left hand 85 thread 19 and locking nut 20, a stem 21 projecting downward through said shaft 16. Upon the lower end of the stem is fixed a 90 chuck or head 22 by any suitable means, preferably a left handed thread 23. Fitted 95 transversely through the chuck 22 is a bar 24 held in place as by means of a screw 25. The innermost face of the bar is spaced from the axis of the stem and chuck.

It will be understood that the stem is held 95 stationary with respect to the motor casing and that the shaft 16 is adapted for rotation at high speed from the motor shaft 12. Fixed to the shaft 16 and constituting an extension thereof is a substantially cylindrical 100 head 26, the means for securing it to the shaft 16 being indicated as a coupling 27 having an internal thread 28 for connection to the lower end of the shaft and having an external thread 29 for co-operation with the 105 internal thread 30 tapped into the upper end of the head, the extent of the thread 30 being great enough to provide for any necessary adjustment axially between the shaft and the head. The interior of the head being 110

hollow provides space for the chuck 22 and parts associated therewith.

31 indicates the pad or contact piece for the can seal C. This pad has a substantially flat cylindrical lower end 31^a and an upper beveled or outwardly flared portion 31^b. Fixed in any suitable manner to the center of the pad is a shank 32 in alignment with the stem 21 and having its upper end cut away at 33 toward the axis for up and down slidable co-operation with said inner face of the bar 24, the reduced upper end of the shank having therefore axial play within the chuck 22, but the stem and shank are locked so that the pad is held stationary with and by the stem 21, except for a slight angular movement incident to a clearance of about $\frac{1}{16}$ inch observed between the bar 24 and the face 33 to facilitate the drifting of the pad into the seal depression.

34 indicates the main body portion of the rotating device formed with or to which is connected a cruciform bearing member 35. This structure includes two diametrically opposite pairs of bearing lugs 36 between each pair of which is an arm or first class lever 37 pivoted on a horizontal pivot 38 fitted in a block 39 and adjustable radially of the axis of the machine by any suitable means. As shown best in Fig. 4 the adjustment of this block 39 toward the axis of the machine is effected by means of a thimble 40 tapped into the outer end of the sleeve 41 and having direct thrust against the outer end of the block. This movement of the block is against the expansive force of a spring 42 located between the block and the main portion of the bearing member 36. To lock the thimble from accidental movement a locking screw 43 is tapped through the knurled outer end of the thimble and into the block 39. The sleeve 41 is formed with upper and lower slots 44 for the free accommodation of the arm 37, the arm being designed to oscillate through a short arc in a vertical plane coincident with the axis of the machine. Journaled upon the lower end of the arm 37 is a double conical finishing roller 45 having the function of effecting the sealing action, the axis of this roll being in the vertical plane aforesaid but arranged at an obtuse angle to the general axis of the arm. In other words, the lower end of said axis is flared outward from the edge of the pad toward which the roll is designed to operate in practice, the beveled portion 31^b of the pad being adapted to be received between the two conical parts of the roll. The upper end of the arm 37 is connected by a toggle link 46 with the lower portion of the head 26, the link consisting preferably of two pivoted parts having right and left threads connected adjustably by means of a turn buckle 47 whereby the effective length of the link may be determined and whereby the action of the roll in

practice may be kept perfectly true. It will be understood that there are two arms 37, but the above specific description of one will be applicable to the other. I wish it to be understood however that I do not propose to be unnecessarily limited to any particular number of such operating parts.

Pivoted in the other pairs of bearing lugs 48 are arms 49, the pivots being indicated at 50. To the lower end of each arm 49 is journaled a conical starting roll 51, the axis of which is flared outward from the pad approximately the same as that of the finishing roll. Each roll 51, however, is of single tapered form and its function, as shown in Fig. 7, is to act initially upon the free edge or outer flange c of the seal, bending it inward toward the neck N in the top of the can while the pad is in the depressed upper surface of the seal. The head 26 carries on its lower end a pair of double cams 52 so designed as to force the upper ends of the arms 49 outward when relative endwise movement is produced between the head and the body 34 to which the arms are pivoted. Any suitable means may be provided to produce such relative vertical movement and consequently between the plunger and the can, the consequent effect being that the pad when forced downward relatively to the position of Fig. 8 and lying within the seal and within the neck will hold the seal stationary or from rotation while the starting and finishing rolls are revolving at high speed around and in contact with the outer flange c thereof. The upper ends of the arms 49 are drawn normally toward the head 26 by means of springs 49', and when they pass over the crests of the cams 52 the rolls 51 will swing outward again.

Relative movement of the head 26 and body 34 toward each other is resiliently resisted by means of a coil spring 53 surrounding a sleeve 54, one end of the spring bearing against a collar 55 adjustable within the upper end of the body 34 and having its upper end bearing against a bushing 56 locked within the lower end of the head 26 by suitable means such as splines 57 held in place by screws 58 and projecting into grooves 59 formed in the sleeve 54. These splines hold the head and bushing from rotation on the sleeve 54 but the head and bushing are permitted to partake of the aforesaid relative endwise movement. The bushing is further locked in place by means of a thimble 60 tapped into the upper end of the sleeve. A thrust bearing 31^a located between the plunger 31 and the body 34 takes care of the rotation of the latter without excessive friction.

In the modification of Fig. 5 the motor casing 10' is provided with a bearing 61 for the motor shaft 12' whose pinion 13' is located below the motor casing. The lower

end of the motor casing is provided further with a head 11' projecting upward within it and in which is fitted a bushing 62 which carries the thrust bearing ring 14'. The 5 bushing may be locked in place by any suitable means such as a pin 63, and fitted as by a left hand thread in this bushing 62 is a stem 21' which is thus held stationary for the purposes set forth in connection with the description of Fig. 1. Around this stem operates a shaft 16' to the upper end of which is fixed a gear 17' meshing with the aforesaid pinion and bearing the other ring portion 15' of the thrust bearing. 10 This figure is an indication that various types of motors or motor casings may readily be adapted for operating my improvement and including means for holding the seal pad stationary.

20 From the foregoing specific description of the mechanism the mode of operation of the improvement will be readily understood from the diagrams of Figs. 6, 7, and 8. A can with a seal C placed loosely upon 25 the neck N is positioned upon or within any suitable platform or support, not shown, beneath the pad, and then by suitable means including usually a foot piece, also not shown because usually conventional, the can 30 and pad are given a relative vertical movement causing the pad to be forced downward relatively as shown in Fig. 7 and with the seal in place in the neck but holding it stationary or free from rotation. During 35 this time the starting rolls 51 crimp the outer flange or periphery c of the seal downward toward the outer surface of the can neck and close to the line of connection between the neck and the horizontal portion 40 of the seal. The rolls being revolved at a high speed around the seal while the seal and can are held stationary by the pad, the crimping and bending action is performed almost instantly, the final or actual 45 sealing action being performed by the finishing rolls 45 coincident with the bending or flaring outward of the can neck N by the action of the flaring portion 31' of the pad, the upper conical portion of 50 each roll 45 bearing on top of the seal and neck while the lower conical portion of the same roll bears firmly beneath what is by this time the under-cut form of the seal and neck. It is to be noted furthermore 55 that not only are the parts of the neck and seal thus brought into firm and intimate contact, but because of the high speed at which the rolls are revolved there is in effect a substantial amalgamation of the metal 60 making a practically homogenous joint and one that is proved air tight without the use of any solder or other extraneous sealing medium. As indicated in Fig. 8 it will be appreciated that with the neck N flared 65 outward and with the free edge thereof

thereby put under stretch and with the free edge or rim portion of the seal crimped beneath it, the seal by no possibility can either become loose or lost from the neck.

For the vertical adjustment of the pad 70 with respect to the body the sleeve 54 is provided with a thimble 64 tapped into the lower end of the sleeve and having at its lower end a turning flange 65 against which bears the uppermost member of the thrust bearing 66. The thimble has an easy fit on the shank 32 and carries a pin or screw 67 projecting into a groove 68 extending around the lower end of the shank whereby the shank and pad are limited from slipping 75 downward. After the adjustment of the thimble is effected a locking nut 69 upon the thimble is turned upward snugly against the lower end of the sleeve 54.

During the sealing action the flare 31' 85 of the pad acts in cooperation with the roll 45 to produce the flare of the neck, it being important that the active face of the roll 45 be maintained parallel to the flare of the pad and spaced therefrom according 90 to the thickness of the metal being crimped between them. For this reason it is important that the roll 45 be so adjustable as to maintain the parallelism just stated even though there may be variations in the thickness of the stock of metal being treated from time to time. The adjustment of the crimping means at the bearing 38 and at the toggle 46 takes care of this important feature.

In Fig. 10 I indicate a modification of a 100 can the neck N' of which is formed vertical at its lower portion and outwardly flared at its periphery, the flare being indicated at approximately 27° from the vertical, though I wish it to be understood that this 105 angle is suggested merely as an illustration and not as a necessary limitation. The lid or seal C' likewise is formed with a vertical portion and a flaring portion leading outward therefrom at about the same angle 110 as above specified and from the top of which projects outward and downward the flange c as already described. This Fig. 10 corresponds to the illustration of Fig. 6 in so far as the stage of operation or assembly 115 is concerned. Fig. 11 is an indication of the next stage and corresponds in this respect to Fig. 7, and illustrates the form of can neck and seal indicated in Fig. 10.

120 I claim:

1. In sealing mechanism for a can having a top with a vertical neck therein and a seal in said neck and having a vertical side adjacent to said neck and an outer flange, 125 means to hold the seal from rotation in the neck, and means to crimp the outer flange of the seal into contact with the outer surface of the neck and flare the neck and both parts of the seal embracing the same, said crimp- 130

- ing means comprising a member revolved around the seal and its holding means.
2. Mechanism as set forth in claim 1 in which the crimping means includes a starting member for initially bending the outer flange of the seal toward final position and a finishing member for effecting the sealing action.
3. A device as set forth in claim 1 in which the seal holding means is a pad including an outwardly projecting flange serving to flare the neck of the can and seal flanges outward while the outer flange of the seal is being crimped around the can neck.
4. A device as set forth in claim 1 in which the seal holding means is a pad having a cylindrical bottom portion and an upper portion flared outward therefrom, the flared portion of the pad serving to flare the neck of the can and seal flanges outward during the sealing action.
5. In can sealing mechanism, the combination of a head, a body connected to the head and movable relatively toward the same, means to rotate the head and body, a seal holding member including means extending through the head and body, means to hold the seal holding member stationary, seal crimping means carried by the body, and adjustable toggles acting between the head and the crimping means to cause the crimping means to function when the body is moved relatively toward the head.
6. Means as set forth in claim 5 in which the means for rotating the head and body is a motor having a casing, and the means for holding the seal holder stationary includes a member rigidly fixed to the motor casing.
7. In can sealing mechanism, the combination of a head, a body connected to the head and movable relatively toward the same, means to rotate the head and body, a seal holding member including means extending through the head and body, means to hold the seal holding member stationary, seal crimping means carried by the body, and means acting between the head and the crimping means to cause the crimping means to function when the body is moved relatively toward the head, the means for holding the seal holder stationary including a fixed stem and a shank in alignment therewith, the stem and shank being movable relatively toward and from each other and having means to prevent relative rotation between them.
8. Means as set forth in claim 7 in which the means for holding the seal holder from rotation includes a fixed stem, a chuck fixed to one end thereof, a cross bar fitted transversely in said chuck, and a shank having an end portion fitted loosely within said chuck and adapted to contact with said cross bar.
9. A device as set forth in claim 7 in which the means for holding the seal holder from rotation includes a member fixed in position, a chuck secured to said member and having a cross bar projecting laterally therethrough, the inner face of the cross bar being spaced laterally from the center of the chuck, and a shank extending from the seal holder into said chuck, the end of the shank within the chuck having a flat face adjacent to but slightly spaced from said cross bar.
10. In can sealing apparatus, the combination of a pad for holding the seal substantially stationary, said pad being so formed as to cause the can neck and seal to be flared outward at the joint during the sealing action, means co-operating with the pad for crimping the outer flange of the seal into intimate contact with the can neck, and means co-operating with the pad for adjusting the same longitudinally with respect to the crimping mechanism.
11. A device as set forth in claim 10 in which the means for controlling the position of the plunger includes a sleeve, a member adjustable endwise of the sleeve and having co-operation with the plunger, and means to lock the member from endwise movement with respect to the sleeve.
12. Mechanism as set forth in claim 10 in which the plunger includes a shank whereby the plunger is held from rotation, a sleeve surrounding the shank, a thimble having threaded co-operation with the sleeve for adjustment of the thimble, means to hold the plunger shank upward within the thimble, and means to lock the thimble from accidental movement.
13. Mechanism as set forth in claim 10 in which the means for controlling the position of the plunger includes a shank, a sleeve surrounding the shank, a thimble having a slidable fit upon the shank and tapped into the end of the sleeve, said thimble having a turning flange at its end adjacent to the plunger, a member projecting inward from the thimble and engageable in the shank, and a thrust bearing between the plunger and said turning flange.
14. In sealing mechanism for a can having a neck to be flared with a predetermined flare and a seal therefor, the combination of a seal-holding pad having a flare to form the neck flare, seal crimping means carried by the body and including a lever and a roll journaled upon the lever, said roll having an active face parallel to the pad flare when spaced therefrom according to the thickness of the stock being crimped, means to rotate the body and crimping means around the axis of the can neck and seal and means to so adjust the crimping roll with respect to the neck axis as to maintain proper parallelism between the face of the roll and said

pad flare irrespective of variations in thickness of the stock.

15. In can sealing mechanism, the combination of a body, means to rotate the body around the axis of the can, seal crimping means carried by the body and including an arm pivoted on a horizontal pivot on the body, a roll journaled upon the arm and thereby revolved around said axis, and means to adjust the pivot of the arm toward or from said axis, the means for adjusting the arm pivot including a block in which the pivot is fixed, and a thimble having threaded engagement with the body and bearing 15 against one end of the block.

16. Mechanism as set forth in claim 14 in which the means for adjusting the arm pivot includes a block carrying the pivot, a spring located between the block and the 20 central portion of the body and tending to force the block outward from the axis, and a member bearing against the outer end of the block and having threaded engagement with the body for forcing the block toward 25 the spring.

17. Mechanism as set forth in claim 14 in which the means for adjusting the arm pivot includes a sleeve fitted within the body, a block slideable radially of the body within the 30 sleeve, a thimble bearing against the outer end of the block and tapped within the outer end of the sleeve whereby the thimble tends to force the block toward the axis of the body, and means to lock the thimble from accidental rotation.

18. In can sealing mechanism, the combination of a body having a double cam arranged parallel to its axis, means to rotate the body around the axis of the can, seal crimping means carried by the body and including an arm pivoted on a horizontal pivot on the body, and a roll journaled upon the arm at one end while the other end of the arm co-operates in succession with the two cams aforesaid first to cause the roll to approach the seal and subsequently to move

outward therefrom while the second cam is acted upon.

19. Mechanism as set forth in claim 18 including a sealing roll revolved also by the body and made effective while the first mentioned roll is moving outward from the seal. 50

20. In sealing mechanism for a can having a top with a neck and a seal member in said neck having a flange extending exteriorly of said neck, means adapted to engage the interior of said seal and said flange, and means coacting with the first mentioned means adapted to engage the exterior of said neck to crimp said flange to said neck, said coacting means simultaneously flaring said neck and seal. 55

21. In sealing mechanism for a can having a top with a neck and a seal member in said neck having a flange extending exteriorly of said neck, means adapted to engage the interior of said seal and said flange, and means coacting with the first mentioned means adapted to engage the exterior of said neck to crimp said flange to said neck, said coacting means simultaneously flaring said 60 neck and seal, said coacting means comprising a pad adapted to be pressed against said seal and one or more pivoted rollers adapted to be urged against said flange, said pad being beveled and said rollers having 65 grooves formed therein shaped to conform to the bevel in said pad.

22. In sealing mechanism for a can having a top with a vertical neck therein and a seal in said neck and having a vertical side 80 adjacent to said neck and an outer flange, means to hold the seal in the neck, and means to crimp the outer flange of the seal into contact with the outer surface of the neck and flare the neck and both parts of 85 the seal embracing the same, said crimping means comprising a member revolved around the seal and its holding means.

In testimony whereof I affix my signature.

RICHARD L. CLEMENTS.
